Specification for Design.

Patented June 23, 1914.

Application filed April 9, 1914. Serial No. 830,810. Term of patent 14 years.

To all whom it may concern:

Be it known that I, JOHN W. PALMER, a citizen of the United States, residing at Chicago, in the county of Cook and State of Illinois, have invented a new, original, and ornamental Design for Coasters, of which the following is a specification, reference being had to the accompanying drawing, forming a part thereof.

Figure 1 is a perspective of a coaster, embodying the new design. Fig. 2 is a vertical section.

The coaster is characterized in having a ribbed central portion A surrounded by a rim B and an annular marginal portion C outside of the rim B.

I claim—

The ornamental design for a coaster, as shown and described.

JOHN W. PALMER.
